UNITED STATES PATENT OFFICE.

WILLIAM W. JACKSON, OF PHILADELPHIA, PENNSYLVANIA, ASSIGNOR TO
MACKELLAR, SMITHS & JORDAN, OF SAME PLACE.

DESIGN FOR A FONT OF PRINTING-TYPE.

SPECIFICATION forming part of Design No. 14,410, dated November 13, 1883.

Application filed September 13, 1883. Term of patent 14 years.

To all whom it may concern:

Be it known that I, WILLIAM W. JACKSON, (assignor to MACKELLAR, SMITHS & JORDAN,) of the city and county of Philadelphia, Pennsylvania, have invented and produced a new and original Design for a Font of Printing-Type, of which the following is a specification.

The nature of my design is clearly shown in the accompanying typographic impression, to which reference is made; and it consists of a condensed letter having a light curved-line ornament terminating in a heavy dot ornamented by a series of light aesthetic ornaments, as clearly shown.

15 The character of the design is preserved in the lower-case and numerals, notably in the e, f, g, j, k, p, q, r, t, y, and z, and in the numerals 2, 5, and 7: but the aesthetic ornaments are omitted.

20 In connection with the font, three ornamental adjuncts are shown—one upon the left hand, the others upon the right hand, of the numerals. The first consists of a scroll-like figure the face of which is shaded by a series 25 of light lines and crossed about centrally by

the heavy dart-like figure; the second of a semicircular line the ends of which terminate in the heavy dots. In the center of the inner boundary of the figure is placed a circular figure, from which radiate a series of heavy and light lines terminating in the inside of the semicircular figure. From the outer surface of the semicircular figure extends about centrally the short line terminating in the heavy dot. The third consists of a circular figure 30 or ring having in its center a heavy ring, from which extend a series of light lines terminating upon the interior of the circular figure. Above and below the circular figure extend about centrally the short lines terminating in 35 the heavy dot.

Having now described my invention, I claim as new—

The design for a font of printing-type, as shown and described.

WM. W. JACKSON.

In presence of—

C. F. HUCH,

HERMAN METIUS.
